SEAR ACTUATED ELECTRIC FIRING DEVICE

John R. Bird, Belmont, Mass.

Application December 3, 1948, Serial No. 63,423

2 Claims. (Cl. 89—135)

(Granted under the act of March 3, 1883, as
amended April 30, 1928; 370 O. G. 757)

1

The invention described in the specification and claims may be manufactured and used by or for the Government for governmental purposes without the payment of any royalty thereon.

This invention relates to a sear mechanism for an electrical discharge device utilized for firing of rockets from a rocket launcher and similar devices.

It is an object of this invention to provide a sear mechanism for an electrical discharge device for rocket launchers.

A particular object of this invention is to provide a sear mechanism for disconnecting the trigger from an electrical discharge device whereby the trigger will return to its normal position without effecting another electrical pulse.

The specific nature of the invention as well as other objects and advantages thereof will clearly appear from a description of a preferred embodiment as shown in the accompanying drawings in which:

Fig. 1 is a longitudinal sectional view of the electrical discharge device shown secured to the underside of a rocket launcher barrel with the trigger in normal position.

Fig. 2 is a detail view similar to Fig. 1 showing the position of the trigger mechanism in the fully retracted position of the trigger.

Fig. 3 is a detail perspective view of the sear and related elements.

Fig. 4 is a detail view similar to Fig. 1 showing the armature about to be rocked, and the position of the trigger immediately before the sear is disengaged from the rocker arm upon rocking of the armature.

This invention essentially comprises a rod-like sear member having a lug portion thereon engageable with the rocker arm of an electrical firing device utilized for generating an electrical impulse for firing a rocket projectile from a rocket launcher. Such sear is pivotally secured to a trigger and is arranged to contact a screw having a conically shaped head whereby the sear is cammed out of engagement with the armature of the electrical discharge device after the electrical impulse has been generated, the sear acting to disconnect the trigger from the armature so that no impulse will be generated on the return of the trigger to the normal or firing position.

There is shown in assembled relation in Fig. 1 an electrical discharge device utilized with a rocket launcher employed by the armed forces

2

embodying the sear mechanism of this invention. The electrical discharge device essentially consists of a frame 10 which includes spaced parallel bars 11 and 12 separated at each end by a magnet 13 and 14. Frame 10 is mounted on the underside of a barrel 15 of a rocket launcher (not shown) and a depending lug 16 welded to the underside of barrel 15 is utilized for such purpose. Frame 10 is secured to lug 16 by a clamp 17.

A field coil 18 is supported within frame 10 midway between magnets 13 and 14 and an armature 19 is mounted within coil 18 for movement through a limited arc therein. A pivoted rocker arm 20, pivoted in the frame 10 as at 20' of substantially U-shape construction is connected at each end of armature 19 by a correspondingly shaped wire spring 21 pivotally attached to the rocker arm 20 by means of a cotter pin 20". 20 There is however an upwardly projecting arm 22 provided on rocker arm 20 and a sear notch 23 is provided in the extreme upper end of arm 22 for a purpose to later appear. A cover 24 normally surrounds frame 10 but is only shown broken away as illustrated in Fig. 1. Near the bottom or rocker arm 20 there is provided a spring 25 which acts against the cover 24 as well as against rocker arm 20 to bias armature 19 in the position shown in Fig. 1 and to normally retain such armature in such position.

A trigger 26 is pivotally secured to the forward end of lug 16 by a transverse pin 27. Trigger 26 depends from lug 16 and substantially in the center of such depending portion of the trigger 35 there is provided a recess 28 for a purpose to shortly appear. A sear 29 is slidably mounted in cover 24 for transverse movement with respect to frame 10. Sear 29 comprises essentially a square rod-like portion 30 having a forwardly 40 projecting end 31 of round configuration and of substantially smaller diameter than the width of the square portion of such sear. Rod 30 terminates in a cylindrical head 32 in which there is provided an axially disposed hole 33. The 45 round portion 31 of sear 29 projects through a slot 43 provided in cover 24. The cylindrical head portion 32 reposes in recess 28 and a transverse pin 34 passes through trigger 26 and hole 33 on the head portion 32 whereby sear 29 is pivotally 50 secured to trigger 26. A spring 35 surrounds end 31 and acts between head 32 and cover 24 to bias trigger 26 away from such cover. The shoulder formed at the junction of round and square portions of sear 29 bears against the inside of 55 cover 23 on opposite sides of slot 43. Thus such

shoulder acts as a stop whereby the clockwise movement of trigger 26 is limited.

Sear 29 is provided with a depending lug or hook 36 having a sloped surface 36' and a shoulder 37. Such shoulder is engageable with the sear notch 23 provided in the upstanding arm 22 of rocker arm 20. A sloped cam surface 38 is provided on the extreme rear end of rod-like portion 30 and is engageable with a cam 39. Such cam comprises a screw which is threadably secured to bar 11 of frame 10 as shown in Fig. 1 and opposite to sear 29. The end 42 of cam 39 is conically shaped as shown in the drawings. A yoke-like spring 40 is secured to the top of bar 12 of frame 10 as by a rivet 41. Spring 40 bears against the upper surface of the sear 29 as shown in Fig. 1 for maintaining sear 29 in engagement with the pivoted arm 20 and subsequently with the cam 39 as shown in Figure 2.

When the trigger is pulled rearwardly shoulder 37 of the sear 29 being in engagement with the sear notch 23 of the rocker arm carries rocker arm 20 with the sear a distance to sufficiently stress the spring 21, as at 21' in Figure 4, causing said spring to snap the armature 19 to a position opposite its normal position whereupon sloped end 38 of sear 29 engages conical end 42 of the cam 39. Thus sear 29 is deflected upwardly whereby shoulder 37 is disengaged from sear notch 23. When the armature is snapped to a position opposite its normal position, the portion of the spring 21 extending below cotter pin 20' engages the rocker arm and compresses spring 25 which in turn causes the spring 21 to snap the armature back to its normal position shown in Figure 2 with the trigger still in pulled position. When the trigger is released the sear 29 is pulled forward by means of spring 35, the sloped surface 36' riding over the frame 22 adjacent the sear notch and the shoulder 37 subsequently engaging the sear notch. Thus it is obvious that electrical impulses are generated only when the trigger is pulled rearwardly and not upon release of the trigger. Formerly an electrical impulse was generated when the trigger was pulled rearwardly and another electrical impulse was generated when the trigger was released thus involving the dangers of hang fire.

From the foregoing description it is clearly apparent to those skilled in the art that there is here provided a simple yet positive sear mechanism for an electrical firing device utilized with rocket launchers and the like for discharging the rocket fixed therefrom.

I claim:

1. In an electrical firing device for a rocket launcher having a frame, a coil mounted on the

frame, an armature mounted within the coil and movable through a limited arc, a spring normally maintaining the armature in one position, and a rocker arm connected to the armature, the improvement comprising a trigger pivotally mounted on the frame, a sear pivotally secured on one end to said trigger, said sear being provided with a rod-like member with a sloped cam surface on the free end thereof and having a downwardly disposed hook portion intermediate the ends engageable with the rocker arm in the normal position of the armature, cam means engageable by said cam surface of said sear in the pulled position of said trigger whereby said sear is disengaged from the rocker arm, resilient means maintaining said sear against said cam means, and spring means surrounding said sear urging said sear and said trigger to the unpulled position.

2. In an electrical firing device for a rocket launcher having a frame, a coil mounted on the frame, an armature mounted within the coil and movable through a limited arc, a spring normally maintaining the armature in one position, and a rocker arm connected to the armature, the improvement comprising a trigger pivotally mounted on the frame, a sear pivotally secured on one end to said trigger, said sear being provided with a rod-like member with a sloped cam surface on the free end thereof and having a downwardly disposed hook portion intermediate the ends engageable with the rocker arm in the normal position of the armature, a screw secured in the frame and opposed to said sear, said screw having a conical end portion adjacent said cam surface of said sear whereby said sear is cammed out of engagement from the rocker arm in the pulled position of said trigger, resilient means maintaining said cam surface of said sear against said conical end of said screw, and spring means surrounding said sear urging said sear and said trigger to the unpulled position.
